UNITED STATES PATENT OFFICE.

J. A. DE BRAME, OF NEW YORK, N. Y., ASSIGNOR TO HIMSELF AND BENJ. GURNEY, OF SAME PLACE.

SKATE.

Specification of Letters Patent No. 32,495, dated June 4, 1861.

To all whom it may concern:

Be it known that I, J. A. DE BRAME, of New York, in the county of New York and State of New York, have invented a new and useful Improvement in Fastenings for Skates; and I do hereby declare that the following is a full, clear, and exact description thereof, reference being had to the accompanying drawings, making a part of this specification, in which—

Figure 1 shows a bottom view of a skate having my improved fastening applied to it. Fig. 2, is a longitudinal section, through Fig. 1, in the vertical planes indicated by the 15 course of red line *x*, *x*, thereon—showing the improved device for fastening the skate to the boot at the heel. Fig. 3, is a perspective view of the heel plate which is secured to the heel of the boot. Fig. 4, is a view showing 20 the plate and its fastening, which are secured to the heel part of the skate iron.

Similar letters of reference indicate corresponding parts in the several figures.

This invention relates to an improvement 25 in securing skates to the soles of boots wherein sliding metallic buttons, which are affixed to the skates, are made to catch into slots in plates which are secured to the bottom of the boots, thereby securing the skates to the boots 30 without straps or clamps as hitherto, as will be hereinafter fully explained.

To enable those skilled in the art to make and use my invention I will proceed to describe its construction and operation.

35 A is a common skate iron, having elevations at *a* and at *b*, which respresent respectively the ball and heel parts of the skate. On the part *a* a flat plate *B*, is suitably secured which should be sufficiently large to 40 form a good bearing for the front part of the foot. One or more hooked projections *c* project from the top of plate *B*, and curve backward, or toward the heel part of the skate, as shown in Fig. 2, of the drawings. This 45 hook *c* catches into a recess *d* formed in a plate *C* which is secured to the sole of the boot, and when the skate is attached to the boot and the hook introduced into the recess in plate *C* this hook *c* will prevent the boot 50 from slipping forward on the plate *C*. At the same time the hook *c* will secure the skate firmly to the front part of the boot.

A plate *D*, is suitably secured on the heel elevation *b*, and this plate should be of a 55 suitable size for supporting the heel of the

boot. The top surface of this plate *D*, is flat like plate *B*, and in the front part of the plate *D* a heel pin *E* is fixed, which projects up perpendicularly from plate *D* and enters a hole in the heel of the boot 60 when the skate is on. A longitudinal dovetail slot *e*, shown in Figs. 2 and 4 of the drawings is formed in the upper surface of plate *D*, which extends through this plate, and in this slot *e* is a sliding block *f*, two of 65 the edges or sides of which are beveled to fit the corresponding beveled sides of the slot *e*. This keeps the block *f*, in its slot and allows this block to be moved longitudinally back and forth in its slot.

70 On the upper surface of the sliding block *f* and projecting up therefrom a suitable distance is a metallic button *g*, having a small neck *g'*, shown in Figs. 2 and 4 of the drawings. This button and its neck should be 75 made very strong and securely fixed to the sliding block *f*. A pin *h* having a suitable head *h'* on one end and a male screw thread on the other end is screwed into the back of block *f* and the stem of the screw passes 80 loosely through the metal portion *D* as shown in Fig. 2, thus having the button *h'* outside of the plate *d*. Now by means of this headed pin *h*, the block *f* may be moved back and forth in its slot or by turning the pin *h*—the screw working in block *f* this block may be adjusted longitudinally. A strong helical spring *i* is coiled around that portion of pin *h* which is between block *f* and fixed plate *d* which spring will 85 forcibly move the block *f* forward when it is drawn back and released.

90 A heel plate *G* which may be made quite narrow, is secured to the bottom of the heel of the boot, in the middle of the heel and through this plate a slot *k* is cut in a direction with the length of the plate, the rear end of which slot terminates in an enlarged hole *n*, of sufficient size to freely admit the button *g* on block *f* and the slot *k* is made 95 large enough to admit only the neck *g'* of this button *g*, thus when the button *g*, is passed through hole *n* in plate *G* the neck of this button *g* will slip into the slot *k*. The upper surface of plate *G* should 100 be inclined toward its rear end, so that when the button head *g* is passed through this plate and moved forward, the head will draw the plate *G* and *D* tightly together.

105 In putting the improved skate on the boot 110

having plates C and G secured to its sole as above described, the hook *c* is first passed into the hole *d* through plate C, the heel of the skate is now pressed up against the heel of the boot and pin E is inserted into its hole. The pin *h* is drawn backward moving the block *f* and button *g*, with it until the button *g*, passes through hole *n* through plate G, when the pin *h* is released, 10 and the spring *i* allowed to force the neck of the button *g* forward and into the slot *k* in plate G. The button *g* will thus secure the heel part of the skate to the heel of the boot. To take off the skate it is only necessary to draw pin *h* back until the button *g* 15 will slip out of the hole *n* in plate G, then detach the hook *c* from plate C, when the skate will come off.

By using the sliding button *g*, I dispense 20 with spring catches of latches which have hitherto been used and their attending objections and I am enabled to make a very secure fastening which is simple and easily operated and where the heels of boots are

very low as in the case of ladies' boots, 25 and the common latch fastening could not be used, my improved fastening will answer a very good purpose for securing the skates at the heels.

I am aware that fixed button fastenings 30 have been used in conjunction with other fastenings for securing skates to the soles of boots and I therefore do not claim, broadly, button fastenings which are fixed on the skate plates or other part or parts of a 35 skate—but

What I do claim as new and desire to secure by Letters Patent is—

The button fastening *g* or its equivalent when secured to a sliding plate *f*, which 40 works in a groove in the skate plate G, and is operated by a pin *h*, substantially as, and for the purposes, herein set forth.

J. A. DE BRAME.
